UNITED STATES PATENT OFFICE.

JAMES ANDREW WHITLING, OF HEALDTON, OKLAHOMA.

PUMP.

1,391,873.

Specification of Letters Patent. Patented Sept. 27, 1921.

Application filed December 10, 1920. Serial No. 429,647.

To all whom it may concern:

Be it known that I, JAMES A. WHITLING, a citizen of the United States, and a resident of Healdton, in the county of Carter 5 and State of Oklahoma, have invented certain new and useful Improvements in Pumps, of which the following is a specification.

My invention is an improvement in 10 pumps, and has for its object to provide a pump especially adapted for use in deep wells, wherein means is provided in connection with the pump for settling the sand before it comes into contact with the valves 15 and piston of the pump, and wherein other means is provided in connection with said piston for preventing the entrance of sand to the plunger or piston and between the packing thereof and the barrel.

20 In the drawings:

Figures 1 and 2 constitute together a longitudinal section of the improved pump,

Figs. 3 and 4 are sections on the lines 3—3 and 4—4 respectively, of Fig. 1,

25 Figs. 5 and 6 are sections on the lines 5—5 and 6—6 respectively of Fig. 2.

In the present embodiment of the invention, the improved pump consists of a tubular casing composed of an upper section 30 1 and a lower section 2, the said sections being connected by a union in the form of a transverse partition 3, onto whose reduced ends the sections are threaded. The union is provided at its center with an opening 4, 35 and the upper end of the opening is reamed and threaded to receive the lower end of the barrel 5 to be later described.

To the lower end of the section 2 a reducing union 6 is connected, the upper end 40 of the union being reduced and threaded to engage the lower end of the section 2. A perforate pipe or anchor 7 is engaged with the lower or small end of the reducing means.

45 A pipe section 8 is threaded into the upper reduced end of the bore of the union 6, and this pipe carries at its upper end a check valve, which is the foot valve of the pump. A cage 9 is connected with the upper end of the pipe by means of a reducing union 10, and within the upper end of this union and within the cage there is arranged a seat 11 in the form of a ring, having an outwardly extending central rib which 50 rests upon the upper end of the union, the seat resting in a counterbore at the upper

end of the union. A ball valve 12 co-operates with the seat, and the cage has longitudinally extending openings for permitting the free passage of liquid when the valve is 60 lifted from the seat.

The pump barrel 5 before mentioned extends upwardly in the section 1, and has connected at the upper end thereof within the section 1 a perforate section 13 by means 65 of a sleeve union 14, and the upper end of the perforate section extends into a reducing union 15 which connects the section 1 with the discharge pipe or casing 16 which conducts the liquid to the top of the well. 70

Within the barrel 4—13 there is arranged a plunger or piston 16 (Fig. 2) the said piston having the usual packing rings 17 held in place between an enlargement on the upper end of the plunger and a collar 18 75 threaded onto the lower end of the plunger or piston, and the rings are spaced apart by collars 19 and 20.

Referring to Fig. 2 it will be seen that two series of rings are provided, the upper 80 series having the rings bent up, while the lower series are bent down, and the collar 20 is arranged between series. A union 21 connects the upper end of the plunger with a hollow piston rod 22, and a check valve 85 23 is arranged within the union, the valve co-operating with a seat 24 similar to the seat 11 and similarly mounted. At its upper end the hollow piston rod 22 is threaded into a union 25—25^a, and with this union 90 there is connected a cage 26 similar to the cage 9 before mentioned. A check valve 27 is arranged within the cage, and co-operates with a seat 28 similar to the seat 11 and similarly arranged.

95 The union 25—25^a is sectional, consisting of an upper section 25 which engages the cage 26 and a lower section 25^a which is connected with a sleeve 29—29^a. This sleeve is a gland, consisting of an upper section 29 and a lower section 29^a which is threaded into the upper section. Packing rings 30 are arranged between the sections, and other packing rings 31 are arranged between the section 25^a of the union and an internal 100 shoulder on the section 29 of the sleeve. The sections 25—25^a of the union have co-operating clutch teeth as clearly shown in Fig. 1 to permit the rod or stem 31 which 105 operates the plunger to be disconnected from the plunger, in cases where the plunger cannot be pulled out of the barrel.

The operation of the improved pump is as follows: When the plunger is moved up liquid is drawn up through the perforated pipe 7 and the standpipe 8, passing out 5 through the cage 9 past the valve 12. The section 2 of the well casing constitutes a sand chamber, as does also the section 1, and the sand may settle in the chambers 1 and 2 about the barrel 5, and about the 10 standpipe 8, between said valve and standpipe and the chamber wall. When the plunger moves downward, the liquid in the lower end of the casing that is within the chamber 2 and within the barrel is forced 15 upwardly through the plunger past the valve 23 and to the hollow piston rod past the valve 27, flowing out into the chamber in the casing section 1.

I claim:

20 1. A pump of the character specified comprising a casing consisting of upper and lower sections, a stand pipe at the lower end of the lower section through which the liquid enters into the said section, said stand pipe 25 extending well above the lower end of the section and having a check controlled port at its top, a barrel extending upwardly from the lower end of the section, the space between the barrel and the said lower end of 30 the lower section being closed, a connection between the upper end of the barrel and the casing, said plunger being hollow and having a hollow piston rod connected therewith and extending to near the top of the 35 upper section of the casing, a section of perforate casing interposed between the upper end of the barrel and the top of the said upper section, a check valve at the top of the hollow piston, and a packing gland at the 40 top of the barrel through which the piston rod moves.

2. A pump of the character specified comprising a casing having a series of compartments arranged one above the other and 45 having a stand pipe extending upward from the bottom of each compartment to form a communication between said compartment and the next lower compartment, the uppermost stand pipe being a pump barrel, and a 50 plunger mounted to reciprocate in the barrel, said stand pipes communicating with the compartments in which they are arranged at their tops, the plunger being ported to

permit the free upward flow of liquid and to prevent its downward flow.

55

3. A pump of the character described, comprising in combination an outer casing, a closure for each end thereof, said closures each having a central passage therethrough, a division wall intermediate the ends of said 60 casing having a central passage, a working barrel communicating with said central passage, a plunger within said working barrel having a hollow stem adapted to force water upwardly therethrough, valve means whereby said water will be held against returning downwardly through said plunger, an education pipe communicating with the upper end of said working barrel, a pipe disposed in the outer casing below the division wall and 65 having its one end communicating with the passage in the lower end of said casing, 70 said pipe being of less diameter than the outer casing and extending upwardly from the lower end thereof to a point below the division wall of said casing, and a check valve adapted to control the flow of liquid 75 through the upper end of said pipe.

80

4. A pump of the character described, comprising in combination an outer casing, 85 a closure for each end thereof, said closures each having a central passage therethrough, a division wall intermediate the ends of said casing having a central passage, a working barrel communicating with said central passage, a plunger within said working barrel having a hollow stem adapted to force water upwardly therethrough, valve means whereby said water will be held against returning 90 downwardly through said plunger, an education pipe communicating with the upper end of said working barrel, a pipe disposed in the outer casing below the division wall and having its one end communicating with the 95 passage in the lower end of said casing, said pipe being of less diameter than the outer casing and extending upwardly from the lower end thereof to a point below the division wall of said casing, a check valve adapted to control the flow of liquid through the upper end of said pipe, and a cage associated with said check valve adapted to cause liquid drawn upwardly through said pipe 100 to spread thereabout for settling the foreign particles therein.

JAMES ANDREW WHITLING.
